UNITED STATES PATENT OFFICE.

HOMER PARMELEE, OF BALTIMORE, MARYLAND.

PIPE-WRENCH.

SPECIFICATION forming part of Letters Patent No. 379,123, dated March 6, 1888.

Application filed February 15, 1887. Serial No. 227,689. (No model.)

To all whom it may concern:

Be it known that I, HOMER PARMELEE, a citizen of the United States, and a resident of Baltimore, in the State of Maryland, have invented 5 certain new and useful Improvements in Pipe-Grips; and I do declare the following to be a full, clear, and exact description of the invention, such as will enable others skilled in the art to which it appertains to make and use 10 to the same, reference being had to the accompanying drawings, and to letters or figures of reference marked thereon; which form a part of this specification.

Figure 1 is a top view of my invention, and 15 Fig. 2 is a side view showing the pivoted spring.

My invention relates to pipe-grips; and it consists in the construction and novel combination of parts as hereinafter set forth.

20 The objects of the invention are to furnish a pipe-fitter's tool that may be handled with ease and rapidity, that may be applied and used in close quarters, that will hold fast without disfiguring the pipe, and will not get out 25 of order.

Referring by letter to the accompanying drawings, A designates the fulcrum-piece of the grip, said fulcrum-piece being provided with extensions B' C', between which the end of an 30 operating-lever is secured.

The fulcrum piece A is provided with, preferably, four aligned lugs or ears, B C D E, along its connecting-piece X, between which lugs the aligned projecting lugs G H I on the section 35 K of the grip are secured by a pivot-bolt, L. To the upper edge of the section K the middle section, M, is hinged, said section M being provided along both of its side edges with aligned connecting-lugs G H I.

To the middle section, M, the third or locking section N is hinged, said section being provided on its normally-free side edge with an outwardly-projecting lip, P, which, when the grip is closed around the pipe, engages a transverse shoulder, Q, on the connecting-piece X 45 of the fulcrum-piece A. The hinged sections K M N are provided on their inner faces with detachably-secured lining-plates Y. These plates may be of any thickness to adapt the grip to different sizes of pipe. A spring, S, 50 is secured to the extensions B' C', respectively, and bears against the outer face of the hinged section K, and prevents it from falling or dropping back, and tends normally to press it toward the pipe being operated upon. The 55 springs must be turned out of the way to remove the grip from the pipe.

Having described this invention, what I claim, and desire to secure by Letters Patent, is—

60 The combination, in a pipe-wrench, of the fulcrum-piece provided with the extensions B' C' for attachment of a lever-handle, and the transverse shoulder Q, the three hinged sections K, M, and N, the outwardly-standing lip 65 on free end of the section N, the pivoted spring S, and the detachable sectioned lining secured to the inner surfaces of said sections, substantially as specified.

65 In testimony whereof I affix my signature in presence of two witnesses.

HOMER PARMELEE.
